UNITED STATES PATENT OFFICE.

ALFRED B. SMITH, OF ABERDEEN, WASHINGTON.

COMBINATION INSTRUMENT.

1,357,481.

Specification of Letters Patent.

Patented Nov. 2, 1920.

Application filed October 16, 1919. Serial No. 330,947.

To all whom it may concern:

Be it known that I, ALFRED B. SMITH, a citizen of the United States, residing at Aberdeen, in the county of Grays Harbor 5 and State of Washington, have invented certain new and useful Improvements in Combination Instruments; and I do hereby declare the following to be a full, clear, and exact description of the invention, such as will enable others skilled in the art to which it appertains to make and use the same.

This invention relates to an improved combination instrument of the pencil type and the principal object of the invention is 15 to provide a combination device of the character described which will constitute a compass and will include a pencil and steel marker which may be used for marking where pencil would not readily show, the 20 steel marker being so constructed and mounted that it will form the pivot point when the device is used as a compass.

Another object of the invention is to provide improved means for locking the steel 25 blade in an extended position thereby preventing the blade from moving out of the desired position when in use as a marker.

Another object of the invention is to so construct this device that the sleeve will be 30 held against rotary movement when in a locked position, thus giving additional strength.

Another object of the invention is to so construct the device that the parts forming 35 the same can not easily come apart, thereby producing a strong and durable device.

This invention is illustrated in the accompanying drawings, wherein:

Figure 1 is a view showing the improved 40 device in side elevation with the marking blade in the folded position and the device ready for use as a compass.

Fig. 2 is a side elevation showing the marking blade in the extended position for 45 use.

Fig. 3 is a longitudinal sectional view through the arm carrying the marking blade with the blade extended and locked.

Fig. 4 is a view similar to Fig. 3 with the 50 blade in the folded position.

Fig. 5 is a perspective view of the locking sleeve removed from the arm carrying the sleeve.

This device is in the form of a compass 55 having arms 10 and 11 which are formed of sheet metal blanks bent to provide the tubular arms having pivot ears 12 and 13 extend-

ing therefrom and positioned in overlapping relation with the pivot pin 14 extending through the ears to pivotally connect the 60 arms. The pencil 15 is inserted in the tubular arm 10 and will be held therein by frictional engagement. The arm 11 is provided upon its outer side and adjacent its free end with a slot 16 to receive the resilient locking tongue 17 carried by the slide 18 and extending through a slot 19 formed in the slide. This slide is further provided with tongues which extend beyond the ends of the arms 11 when the slide is moved downwardly and are adapted to retain the steel marker blade in the extended position as will be hereinafter brought out.

A core 21 is positioned in the arm 11 and rotatably mounted therein and is provided 75 adjacent its lower end with a cutout or pocket 22 which registers with the slot 16 and receives the tongue 17 thus permitting the core to be held against rotary movement when the marker is in the extended position. 80 This core extends beyond the free end of the arm 11 and carries a head 23 which is similar to the end portion of a pen knife and carries a blade 24 which is pivotally mounted and is provided with a spur 25 acting as a pivot 85 point for the compass when the marking blade 24 is in the folded position. A spring 26 similar to the spring of a pen knife is carried by this core and extends into the head to engage the heel of the blade and retain 90 the blade in an adjusted position. From an inspection of the drawings it will be evident that the tongues 20 may fit into the head beneath the blade and against the outer face of the spring 26 when the marker blade 95 is extended as shown in Fig. 2, thereby securely locking the core against rotary movement and preventing the blade from turning from the desired position when the device is in use as a marker.

When the device is used as a compass, the core will be rotated and the marker blade turned inwardly thus extending the spur to provide the pivot point for the compass. When the device is not in use, it will be left 105 in this position and the arms can then be brought together and the device placed in the pocket without any danger of the sharpened end of the marking blade catching and tearing the pocket. When the device is used as a marker for marking wet wood and other substances which could not be readily marked with a lead pencil, the blade will 110 be swung outwardly and the core then ro-

tated so that the blade will extend from the outer side of the arm 11. The sleeve will then be moved downwardly so that the tongues 20 engage the head and the blade 5 will then be securely held in the extended position thus permitting it to be used as a marker. When used in this manner, the two arms will be brought together thus providing a good handle. This device can 10 be used as an ordinary pencil when in the folded position and further when in this position can be used as a pair of dividers as well as being used as a compass. There has therefore been provided a device which 15 will be very convenient for use by carpenters or others having use for similar instruments. It should be further noted that this device may be set with the arms apart a desired distance and moved along a board with the 20 free end of arm 11 engaging the side edge of the board and the pencil extending across the face of the board and making a scribe line as the device is moved.

What is claimed is:

- 25 1. A device of the character described comprising tubular arms pivotally connected at their upper ends, a core rotatably mounted in one of said arms, a head connected with said core and positioned beyond the outer ends of the arms, a marking blade pivotally connected with the head for movement from a position at substantially right angles to the arms to a position substantially parallel to the arms with its free end extending 30 toward the pivoted ends of the arms, a leaf spring engaging the blade to retain the same in an adjusted position, said arm being provided with an opening and the core with a pocket to register with the openings of the 35 arm, a sleeve slidably mounted upon the arm and having its lower end provided with tongues for engaging the head to retain the head against rotation when the marking blade is in an extended position at substantially right angles to the arm, and a resilient tongue carried by the sleeve for passing through the registering opening and pocket to retain the sleeve against rotation when the 40 blade is in the extended position.
- 45 2. A device of the character described comprising tubular arms pivotally connected at their upper ends, a core rotatably mounted in one of said arms and extending beyond the lower end thereof, a head carried by the core and positioned beyond the lower end of the arm, a marking blade having a heel pivotally connected with the head, the heel being provided with a spur for constituting a pivot point when the blade is 50 in a folded position, a sleeve slidably mounted upon the arm, and tongues carried by the sleeve and extending to engage the head for locking the head against rotary movement when the blade is in an extended position.

3. A device of the character described 65 comprising arms pivotally connected at their upper ends, one of said arms being hollow, a core rotatably mounted in the hollow arm, a head carried by the core, a marking blade having a heel pivotally connected with the head and provided with a spur extension constituting a pivot point when the marking blade is in a folded position, a locking sleeve slidably mounted upon the hollow arm for engaging the head to retain the core against 70 rotary movement when the blade is in an extended position, and means for releasably locking the sleeve against rotary movement upon the hollow arm when in engagement with the head.

4. A device of the character described 75 comprising arms pivotally connected at their upper ends, one of said arms being hollow, a core rotatably mounted in the hollow arm, a marking blade pivotally connected with the rotary core for movement from a folded 80 to an extended position, and means carried by the hollow arm for engaging the head to releasably retain the core against rotary movement when the marking blade is in an 85 extended position.

5. A device of the character described 90 comprising arms pivotally connected, one of said arms being adapted to carry a renewable marking implement, a blade carrier 95 rotatably connected with the second arm, a marking blade pivotally connected with the blade carrier and having a spur extension constituting a pivot point for the device 100 when the marking blade is in a folded position, and means for releasably retaining the blade carrier against rotary movement.

6. In a device of the character described, 105 a pair of pivoted members, one of said members carrying a marking element, and a pivoted spur pivotally carried by the other pivoted member and capable of being disposed parallel to said member or at an angle thereto and having an extension forming a marking arm when the spur is extended at 110 an angle to the pivoted member.

7. In a device of the character described, 115 a pair of pivoted members, one of said members carrying a marking element, and a spur pivotally connected with the other pivoted member and capable of being disposed parallel to said member or at an angle thereto, the spur when in the first mentioned position constituting a centering point for the marking element, and the spur having an extension forming a marking element when the spur is in the latter position.

In testimony whereof I affix my signature in presence of two witnesses.

ALFRED B. SMITH.
